TRAFFIC SIGNALING SYSTEM

William S. Halstead, Huntington, N. Y., assignor
of one-third to John B. Brady, Washington,
D. C.

Application March 8, 1939, Serial No. 260,644

10 Claims. (Cl. 177—337)

This invention relates in general to traffic signaling systems and is more particularly concerned with means for effecting traffic signaling by radio and electro-acoustical apparatus.

It is a primary object of this invention to provide radio and electro-acoustical means whereby aural control signals, traffic bulletins or other intelligence may be transmitted at given zones in a lane of traffic.

It is an additional object of this invention to provide means for effecting synchronization of transmission of aural traffic control signals by radio and electro-acoustic apparatus with changes in the operating cycle of a traffic control system employing visual signaling means.

It is a further object of this invention to provide means for conveying to pedestrians and drivers of vehicles aural indication of impending changes in the signaling characteristics of a visible traffic control system.

It is an additional object of my invention to provide a radio traffic signaling system which may be utilized by drivers of vehicles equipped with conventional broadcast receiving equipment.

Other and further objects reside in the constructional and circuit arrangements for effecting coordinated operation of radio and electro-acoustical apparatus with traffic control means as set forth in the specification hereinafter following and by reference to the accompanying drawings in which:

Figure 1 is a front elevational view of a conventional street traffic control light with supporting structure showing attached thereto radio and electro-acoustical apparatus employed in transmitting control signals and other intelligence to motorists and pedestrians at timed intervals as determined by the operating cycle of the associated traffic control light; Fig. 2 is a front elevational view of the interior of a metal case shown on the traffic light support of Fig. 1 said case containing radio and repeating sound record apparatus employed in the system of the invention; Fig. 3 is a plan view of a preferred form of sound recording and reproducing machine enclosed in the lower section of the case shown in Fig. 2; Fig. 4 is a side elevational view of a downwardly disposed speaker employed on traffic light stanchions at dangerous street crossings for the purpose of warning pedestrians of impending light changes or for conveying other intelligence of public service nature to pedestrians within specific zones; Fig. 5 is a schematic diagram of connections of the apparatus employed in the system of the invention showing

combination of radio and electro-acoustic equipment with a vehicular traffic signaling circuit; Fig. 6 is a plan view in schematic form showing a preferred system of buried cables employed as wave-guides or transmission lines in conveying signal energy to vehicles in given traffic lanes; Fig. 7 is a front elevational view of a conventional traffic signal with its supporting structure showing attached thereto a radio transmitter and radiating structure for transmitting radio traffic control signals from a remote central control point to vehicles on the route associated with said traffic signal; Fig. 8 is a side elevational view of the radio transmitting device shown in Fig. 7; Fig. 9 is a schematic diagram showing connections of the transmitter of Figs. 7 and 8 with the power and control circuits provided for operation of the traffic light. Optional connections of an amplifier and loud speaker are also indicated; and Fig. 10 is a schematic diagram illustrating interconnections at a central point of traffic signal-control devices, tone generator and repeating sound record machine with control circuits leading to the remote transmitter installed in proximity to a lane of traffic.

Referring to the drawings in detail, wherein like reference characters indicate corresponding parts throughout the several views, each form of the invention illustrated herewith in Figs. 1 to 5 embodies the combination of a small radio transmitter 10, Fig. 2, an automatic repeating sound record machine 11, such as a magnetic tape or wire recorder of the endless loop type, an amplifier 12, and downwardly-directed loud speaker 13, all associated and interconnected with the traffic control system of which visual signals 14, 15, 16 and 17 are a part. Each form of the invention described herewith likewise illustrates the use of a traffic control tone generator such as audio frequency oscillator 45, Fig. 5, which may be correlated as shown with the operation of a conventional street or railway traffic control system to provide within a vehicle aural indication of the particular signaling characteristic of the external traffic light through transmission of a predetermined tone signal.

In the particular embodiment of the invention shown in Figs. 1 to 5, inclusive, the radio transmitter 10, of any well known type having a power output of several watts at a selected frequency such as 550 kilocycles is disposed in a weatherproof steel case 18, preferably located on traffic light stanchion 19, Fig. 1, or other support in proximity to a lane of traffic 49. Magnetic tape

machine 11 and amplifier 12 may also be enclosed in the same case as shown.

A present preferred form of construction of the magnetic tape sound record machine is shown in Figs. 2 and 3 in which two rollers or cylinders 20 and 21, fabricated of Bakelite or other similar material are horizontally disposed between bearings in frame 22, Fig. 3. Two steel tapes or wires 23 and 23A, which serve as sound record carriers are helically wound around the two rollers to form separate sections as shown. The first and last loops of tape 23 are joined together over cross-over rollers or wheels 24 and 25 thereby forming an endless loop. The first and last loops of tape 23A are joined in similar manner over cross-over rollers 24A and 25A. Recording and pick-up leads 26 and 26A are disposed midway on the cross-over loops of tapes 23 and 23A and are supported in position by bracket 27. Electric motor 28, Fig. 2, drives roller 21 by means of a belt or chain 29, thereby moving tapes 23 and 23A through a predetermined operating cycle.

In the circuit of Fig. 5 the pick-up coil 30 of the magnetic tape machine is connected through control arm 31 of relay 32 to the input circuit of amplifier 12. The output circuit of this amplifier is connected to the speech input circuit of transmitter 10. The coil of relay 32 is connected through electrical time switch 33 of any well-known type to circuit 46 which controls relay 47 and green light 41 disposed so as to control vehicular traffic in lane 49, Fig. 6. Relay 32 also controls the operation of motor 28. In this manner, when the armature of relay 32 is drawn to the left hand transmitting position the magnetic tape machine is automatically started and a brief traffic bulletin, detour instruction warning, light change warning, or other intelligence is transmitted by radio to drivers of vehicles proceeding on lane 49 during a predetermined interval while the green light 41 is in operation. When power is removed from green light circuit 46 relay 32 returns to the right-hand position shown in Fig. 5. In the open position, control arm 38 breaks the circuit to motor 28 which remains inoperative until power is again applied through closure of relay 38. In like manner the magnetic tape machine may be coordinated with the red light circuit 42, if desired, to permit transmission of a given message to vehicles while waiting for a traffic signal to change from red to green.

Pick-up coil 34 of head 26A is connected through contact arm 35 of relay 36 to the input circuit of amplifier 12A, the output circuit of which is connected to loud speaker 13. Relay 36 is connected through time switch 37 to circuit 76 which controls operation of relay 47A and green light 77 of intersecting lane 50, Fig. 6. Power is applied to motor 28 through closure of contact arm 39 of relay 36 when in the left-hand operating position. In this manner, at a predetermined time interval, such as ten or fifteen seconds, before a given signal changes from green to red, relay 36 is closed by operation of time switch 37. Thus the magnetic tape machine is started and pick-up coil 34 is connected to the input circuit of amplifier 12A. Loud speaker 13 is thereby energized and conveys brief safety messages or other intelligence addressed to pedestrians at main traffic intersections. By this method pedestrians about to cross a main thoroughfare at a dangerous intersection may be given an aural warning such as "Do not cross Broadway now. The light is about to change"

ten or fifteen seconds in advance of a change of light from green to red. The same acoustical method may also be employed in conveying emergency traffic detour instructions to drivers of vehicles in the immediate vicinity of the intersection while waiting for a light to change from red to green.

Since the speech record carried by the magnetic tape machine may be instantly changed and a new recording made at the transmitting location by a patrolman with a small microphone facilities are provided for reaching large numbers of pedestrians and motorists in the event of serious traffic congestion, fires, break-down in public transit facilities or other emergencies which commonly occur in large cities.

In the application of the system to railroad signaling aural train dispatching instructions or other intelligence may in similar manner be transmitted by radio or acoustical means to the engineer of a train.

Traffic control tone signals may also be correlated with the operation of red light 40 and green light 41 for radio transmission to vehicles by connection of the output circuit of an audio frequency oscillator 45 to the input circuit of amplifier 12 and by connections with relay 44 in the control circuit as shown in broken lines in Fig. 5. Contact arm 48 of relay 32 is connected to condenser C2 disposed in the oscillating circuit of the tone generator 45. The contact arm of relay 44 is connected in left-hand position to condenser C1 and in the right-hand position to condenser C3, both disposed in the oscillating circuit of tone generator 45. Thus when red light control circuit 42 is energized closure of relay 44 places condenser C1 in the oscillating circuit of the tone generator, producing a characteristic "stop" tone of frequency F1 such as 4000 cycles for transmission to vehicles approaching a red light in lane 49. Opening of relay 44 by removal of energizing current in red light circuit 42 effects movement of the armature of relay 44 to the right-hand position. Condenser C3 is thereby placed in the oscillating circuit to produce a characteristic "go" tone of frequency F3, such as 200 cycles. Energization of green light control circuit 46 initiates the control cycle of timer 38 which after a predetermined interval closes relay 32 and thereby moves contact arm 48 to the left placing condenser C2 in the oscillating circuit of tone generator 45. The emitted signal during a short period immediately in advance of a change from green to red light may thus be given a characteristic "caution" tone of frequency F2 such as 2000 cycles. Drivers of vehicles approaching a traffic signal may thereby be given audible indication of impending change in traffic light ten or fifteen seconds before the change occurs.

The distinguishing characteristics of the various control tones, which may be superimposed on speech signals if desired without noticeably affecting their intelligibility, also provide aural indication of a red or green light on the route ahead to the driver of a vehicle even though he may not be able to see the light in question because of obstructions in his path or for other reasons. In addition, the tones may be employed to control the operation of signal lights disposed within the vehicle, said lights being selectively energized by connections with the output circuit of a radio receiver having frequency discriminating devices attached thereto as is described in United States Patent No. 2,131,042, granted Sep-

tember 27, 1938, and in pending applications Serial Numbers 228,051 and 228,052, filed September 1, 1938.

It is pointed out that the circuit of Fig. 5 illustrates means for coordinating radio and electro-acoustical equipment with operation of traffic signals disposed to control traffic in a given lane such as north-south street 49, Fig. 6, or a particular railway track in the application of the system of the invention to railway signalling. To control traffic in another lane, such as east-west street 50, or a parallel railroad track carrying traffic in an opposite direction a second radio transmitter 10A with similarly coordinated equipment is employed.

Radio signal energy from transmitter 10 cooperatively associated with traffic lights 40 and 41 in lane 49 may be conveyed to vehicles proceeding in a given traffic control zone up to several thousand feet in length by means of cable or cables 51 disposed in the traffic lane as shown in Fig. 6, or otherwise disposed in proximity thereto. Radio signal energy from transmitter 10A by similar means 52 is conveyed to vehicles proceeding in intersecting lane 50. To prevent cross-talk between adjacent transmission circuits one frequency such as 550 kilocycles may be employed for one lane such as 49, and a slightly different frequency such as 560 kilocycles may be employed for intersecting or different lanes.

Radio frequency energy is transferred from the radio transmitter to the cable 51 by employing any well-known coupling means which permits of extremely loose coupling between the output circuit of the transmitter and the cable conductor. Satisfactory results have been attained in practice by connecting one end of a coil of several turns, not shown, to the cable conductor, said coil being disposed adjacent to the antenna loading circuit of the transmitter at a distance sufficient to reduce the coupling to the point where the cable may be attached or detached from its coil without causing any appreciable change in the plate current of the output stage of the transmitter. In this manner, through limitation of the amount of signal energy carried by the cable to an extremely small value the transmitted signal cannot effectively be heard until an approaching vehicle is within approximately a hundred feet of the cable, though a strong and substantially uniform signal is received while the vehicle is proceeding along the cable.

Selection of a particular frequency for use within a given geographical zone is dependent on existing assignments to other services. 550 kilocycles has been specified herein since a signal transmitted at this frequency is particularly suited for reception with existing automobile receivers, it only being necessary to turn the tuning control to the end of the dial or depress an end button on a receiver of the push-button type. The traffic control frequency selected for use within a given zone is posted in proximity to the lane of traffic as shown in Fig. 1, wherein a small sign 53 is disposed on the traffic light housing.

In a modification of the system shown in Fig. 7 a waterproof metal case, 54, enclosing a low power transmitter 56, Fig. 9, is mounted on traffic light stanchion 19, Fig. 8, adjacent to a lane 70 of traffic 49. A radiating element 55, Fig. 9, in the form of a rod or coil, protected by a tubular housing 57, Fig. 8, is employed to transmit signal energy to vehicles within several hundred feet of said transmitter. A cable 51 may also be em-

ployed as is illustrated in Fig. 6, for installations in which a range of several thousand feet is required.

Power for the radio transmitter is obtained by connection with existing power circuit 58 employed to energize the associated traffic lights such as 40 and 41, Fig. 9. Relays 43 and 47 by means of light control circuits 42 and 46 respectively select for energization lights 40 and 41, respectively as shown. Modulating signals such as traffic control tones from tone generator 59, Fig. 10, and aural traffic bulletins from a repeating magnetic tape machine 60, preferably located at a central control point, are applied to the input circuit of transmitter 56 by means of connection with a telephone line 61 or by utilization of the traffic light control circuits 42 and 46 by any well known duplex or carrier technique.

To illustrate the manner in which coordination of control tone and speech transmission is effected in step with changes in the traffic signals a diagram of a simplified control circuit is shown in Fig. 10 wherein a timer 65 of any conventional type is employed to actuate a relay 64 which in turn effects energization of stop signal circuit 42 or go signal circuit 46. Connections of the relay 64 are such that when the armature is in the position shown in Fig. 10 contact arm 63 closes against the right-hand contact thereby applying an E. M. F. from battery 66 to green light control circuit 46. At the same time, tone control arm 67 places condenser C₂ in the oscillating circuit of the audio frequency wave generator 59 thus producing control tone F₂ associated with green light 41. When the armature of relay 64 moves to the left-hand position circuit 42 associated with red light 40 is energized through movement of control arm 63 against the left-hand contact of the relay. Simultaneously, tone control arm 67 moves against its associated left-hand contact thereby inserting C₁ into the oscillating circuit of wave generator 59 to produce a control tone F₁, associated with red light 40. The control tones correlated with each signal are amplified by vacuum tube amplifier 68 and thereafter transmitted by line 61 or by duplex operation over light-control circuits 42 and 46 to the input circuit of transmitter 56, from which point the control signals are transmitted to vehicles. The pick-up coil 69 associated with the recording and reproducing head of the magnetic tape machine 60 is connected to a separate input channel of amplifier 68 as shown.

Timing of transmissions from the steel tape unit may be effected by means of operation of relay 70 connected with time switch 65 through circuit 71. Thus at a predetermined time interval coordinated with the traffic light control cycle aural bulletins from magnetic tape machine 60 may be transmitted.

It is pointed out that while this specification has described an application of the system of the invention to control of automobile traffic, no limitation is thus intended since substantially the same apparatus may be employed in railroad signaling or general communications.

In railroad signaling, the transmitters associated with a given track may be tuned to a suitable predetermined frequency while the transmitters associated with a second parallel track may be tuned to a different predetermined frequency. Thus the engineer of a train on a northbound track, for example, will receive the signal from the proper transmitter without in-

terference from the transmitter tuned to a different frequency intended for signaling to south-bound trains. Such a system may readily be applied in practice because of the present availability of satisfactory crystal-control transmitters having a high degree of frequency stability, and receivers of the push-button type, which permit convenient and accurate tuning change from one given frequency to another without possibility of error.

It will be recognized that the illustrative systems described herein are capable of considerable modification and rearrangement without departing from the spirit and scope of the invention, and it is therefore to be understood that the following claims embrace all such modifications and equivalent arrangements as may fairly be construed to fall within the scope of the invention.

What I claim as new and desire to secure by Letters Patent of the United States is as follows:

1. In a traffic signaling system, a transmitter for emitting a carrier frequency effective substantially within a predetermined zone along a traffic lane to effect automatic communication with vehicular traffic moving in said zone in said traffic lane, a sound storage device having a recorded message thereon for effecting continuous automatic repetition of a given communication addressed to traffic in said predetermined zone, means for modulating said carrier frequency by said sound record storage device, the time for the transmission of said complete recorded message being not greater than the normal time required for a vehicle to negotiate said predetermined zone.

2. A traffic signaling system having a radio transmitter to effect automatic communication with vehicular traffic moving in a given traffic lane, a signal record device for effecting continuous automatic repetition of a given communication addressed to traffic in said traffic lane, means for modulating said radio transmitter by said signal record device, and a transmission line disposed substantially parallel to said traffic lane for the purpose of limiting the effective signaling area to a desired traffic signaling zone, the time for the transmission of said complete communication being not greater than the normal time required for a vehicle to fully negotiate the signaling zone.

3. In a traffic signaling system, a transmitter for emitting a carrier frequency effective substantially within a predetermined zone along a traffic lane to effect automatic communication with vehicular traffic moving in said lane, a sound storage device having a recorded message thereon for effecting continuous automatic repetition of a given communication addressed to traffic in said predetermined zone, means for modulating said carrier frequency by said sound storage device, visual right of way indicating means, means for operating said last mentioned visual means to alternately indicate "stop" and "go" signals to traffic in said predetermined zone, and means for synchronizing the transmission of said recorded message through said transmitter with the operation of said visual "stop" and "go" right of way indicating means.

4. A traffic signaling apparatus for controlling the flow of traffic in a traffic lane and having, in combination, visual right of way indicating means to alternately indicate "stop" and "go" signals to traffic in said traffic lane, a timer for controlling the duration of said "stop" and "go" sig-

nals, switching means controllable by said timer for energizing the "stop" and "go" signals, a source of carrier wave energy, means for emitting said carrier wave energy effective substantially within a predetermined zone along a traffic lane, and means controlled by said timer for modulating said carrier wave in accordance with a plurality of frequencies, two of said frequencies representing "stop" and "go" indications coordinated with said "stop" and "go" visual indications respectively.

5. In a traffic signaling system, a transmitter for emitting a carrier frequency effective substantially within a predetermined zone along a traffic lane to effect automatic communication with vehicular traffic moving in said zone in said traffic lane, a sound storage device having a recorded message thereon for effecting continuous automatic repetition of a given communication addressed to traffic in said predetermined zone, means for modulating said carrier frequency by said sound storage device, the time for the transmission of said complete recorded message being not greater than the normal time required by a vehicle to negotiate said predetermined zone, and a visible marking device placed ahead of said signaling zone and adjacent thereto for the purpose of advising traffic of the presence and frequency of said transmitter.

6. In a traffic signaling system, a transmitter for emitting a carrier frequency effective substantially within a predetermined zone along a traffic lane to effect automatic communication with vehicular traffic moving in said zone in said traffic lane, a sound storage device having a recorded message thereon for effecting continuous automatic repetition of a given communication addressed to traffic in said predetermined zone, and means for modulating said carrier frequency by said sound storage device, said last mentioned means including an amplifier, and a pick-up device connected to the input of said amplifier.

7. In a traffic signaling system having visual "stop" and "go" indicators, a timer for controlling the sequence and duration of operation of said "stop" and "go" indicators in a signaling cycle, switching means controlled by said timer for energizing said "stop" and "go" indicators, a source of carrier wave energy, signal emitting means connected to said source of carrier wave energy and being disposed to emit signaling energy within a restricted zone along a traffic lane in which the flow of traffic is controllable by said visual "stop" and "go" indicators, a source of audio frequency energy, and a second switching means controlled by said timer for varying the frequency of said audio frequency energy in definite predetermined steps, one of said steps having a predetermined audio frequency characteristic correlated with said "stop" indicator, a second of said steps having a predetermined audio frequency characteristic correlated with said "go" indicator, and a third of said steps having a predetermined audio frequency characteristic corresponding to a "caution" indication.

8. In a traffic signaling system as set forth in claim 6, in which the sound storage device includes a magnetic tape and the pick-up device includes a pick-up coil for reproducing signals impressed on said magnetic tape.

9. In a traffic signaling system having visual "stop" and "go" indicators, timing means for controlling the sequence and duration of operation of said "stop" and "go" indicators in a sig-

naling cycle, switching means controlled by said timing means for selectively energizing said "stop" and "go" indicators, a source of audio frequency wave energy, an amplifier connected to said source of wave energy, directional signal transmission means connected to said amplifier for effecting directional transmission of signal energy within a predetermined signaling zone along a traffic lane, and a second switching means controlled by said timing means for varying the frequency of said source of audio frequency wave energy in definite predetermined steps, one step being correlated with the operation of said "stop" indicator, and a second step being correlated with said "go" indicator.

10. In a traffic signaling system having visual "stop" and "go" indicators, timing means for

controlling the sequence and duration of said "stop" and "go" indicators in a signaling cycle, switching means controlled by said timing means for selectively energizing said "stop" and "go" indicators, a sound record device having a magnetic tape, a pick-up head disposed in proximity to said tape, an amplifier connected to said pick-up head, directional signal transmission means connected to said amplifier for effecting directional transmission of signal energy within a predetermined signaling zone along a traffic lane, and a second switching means controlled by said timing means for effecting transmission of intelligence as pre-recorded on said magnetic tape in timed correlation with the selective operation of said visual "stop" and "go" indicators.

WILLIAM S. HALSTEAD.
